UNITED STATES PATENT OFFICE.

ARTHUR RIVINGTON MANGNALL, OF CHESTER, AND ROY FORBES IRVING, OF CLIFTON, BRISTOL, ENGLAND.

EARTH-BORING MACHINE.

1,354,054.

Specification of Letters Patent. Patented Sept. 28, 1920.

Application filed July 31, 1920. Serial No. 400,512.

To all whom it may concern:

Be it known that we, ARTHUR RIVINGTON MANGNALL, A. M. I. C. E., A. M. I. M. E., a subject of the King of Great Britain and 5 Ireland, and residing at 43, White Friars, Chester, in the county of Chester, England, and ROY FORBES IRVING, A. M. I. C. E., a subject of the King of Great Britain and Ireland, and residing at 2, Priory Road, 10 Clifton, Bristol, in the county of Gloucester, England, have invented certain new and useful Improvements in Earth-Boring Machines, of which the following is a specification.

15 This invention relates to earth boring machines of the type in which the bore is produced by the displacement of the earth due to the action of a ram or pusher operated by hydraulic or other means.

20 The object of the present invention is to provide an improved arrangement of the hydraulic cylinder and its carrying mechanism which permits of rapid setting of the cylinder and of the ready and accurate insertion into their operative position of the 25 pipes, rods or the like by which the boring ram is propelled, and which insures the quick displacement of the water from the hydraulic cylinder when a pipe, rod or the 30 like is being placed therein. A further object of this invention is to adapt the arrangement aforesaid for use in the rapid withdrawal of the pipes and boring ram from position after the bore has been produced or 35 for drawing cables, pipes or the like through the bore.

Referring to the accompanying sheet of explanatory drawings:—

Figure 1 is an elevation, and

40 Fig. 2 a plan view of an earth boring machine constructed in one convenient form in accordance with this invention.

Fig. 3 is an elevation, and

45 Fig. 4 a plan view of the machine arranged for withdrawing the tubes or rods from the bore or for drawing cables, pipes or the like through the latter.

Figs. 5 to 8 are similar views showing a slightly modified form of apparatus.

50 The same reference letters in the different views indicate the same parts.

The hydraulic cylinder *a* containing the piston or plunger by which the pipes *b* for propelling the ram or pusher are driven forward, is provided with trunnions *c* which

rest in slots in a frame *d* carried by tubular or like members *e* clamped in place in the hole or pit at the mouth of the bore *f* being produced. The rear end of the cylinder has a projecting part *g* abutting against a stationary member *h* carried by the frame aforesaid, the abutting faces being curved so as to permit of the rotation of the cylinder about the axis of its trunnion. A suitable water inlet connection *i* and an exhaust connection *j* are provided for the hydraulic cylinder with the required control valves thereon. The frame *d* may be carried centrally between the members *e* as shown in Figs. 5 to 8 instead of above the same as 70 illustrated in Figs. 1 to 4.

The forward end of the hydraulic cylinder *a* is held in place in alinement with the bore being produced by a clamp *k* permitting of the accurate setting of the cylinder. Preferably, the clamp is carried by the front end of the frame *d* supporting the hydraulic cylinder or barrel, and is mounted so as to be capable of both horizontal and vertical adjustment movements.

The pipes which are being propelled by the hydraulic plunger are held centrally with relation to the plunger by a plurality of arms *m* pivoted upon the plunger which, when the latter is within the cylinder, project beyond the front end of the plunger so as to form a guide for the pipe end. When, however, the pipe is fully expelled from the hydraulic cylinder, as shown in Fig. 1, the catches *m* project clear of the cylinder and the lower ones can turn freely about their pivots clear of the pipe so permitting of the cylinder being turned about its trunnions to clear the pipe which has been driven into the bore and to rest in an upright position as shown in dotted lines in Fig. 1, where a further pipe can be lowered thereinto as the plunger recedes and the water is released. The dropping of the new pipe length into the vertical cylinder assists in the rapid expulsion of the water from the cylinder.

The tubular elements *e* upon which the frame *d* carrying the hydraulic cylinder *a* rests are preferably two in number disposed in the same longitudinal direction as the said cylinder; the rear end of the frame *d* against which the hydraulic cylinder abuts, beds against the block *o* upon the side of the pit, so as to take up the thrust exerted during working.

When it is desired to withdraw the pipes and boring head after a bore is completed, or if it is desired to draw cables, pipes or the like through the bore, the frame *d* with 5 the hydraulic cylinder *a* thereon is turned to a vertical position as shown in Figs. 3 and 4 and may be arranged as shown in Figs. 3 and 4, or may rest upon a cross-piece on the members *e* as shown in Figs. 7 and 8. 10 A bracket *o* with rope pulley *p* thereon, and also an anchor rod *q* for the rope *r*, are attached to the frame and a pipe or rod *s* carrying the double rope pulley *t* is placed in the cylinder for operation by the hydraulic plunger. The pull exerted on the carriage *d* by the rope *r* is resisted by the tie rods *u* attached to the carriage *d* and to a member *v* secured in position by the tubular elements *e*. With this arrangement, 15 the one hydraulic cylinder and plunger serves both for producing the bore and for removing the pipes therefrom. The frame may be supported at a point higher than its base and the tie rods *u* and pulley bracket *o* 20 be similarly elevated in position.

The invention is not to be limited to any particular arrangement of the supporting frame for the hydraulic cylinder, of the hydraulic connections and control fittings, nor 25 to any particular means for setting and adjusting the position of the cylinder to direct the pipes into the bore, as these and the other details of the improved machine may be modified to suit any special services or 30 requirements.

Having now described our invention, what we claim as new and desire to secure by Letters Patent is:—

1. An earth boring machine comprising a 40 frame having means for clamping the same in a position adjacent to the mouth of the bore to be produced, a second frame adjustably connected to the first frame, a hydraulic cylinder pivotally mounted in the 45 second frame, and a hydraulic plunger in said cylinder.

2. An earth boring machine comprising members adapted to be clamped between opposite walls of the pit adjacent the mouth 50 of the bore to be produced, a frame carried by said members and abutting against the walls of the pit opposite the bore, and a pivotally mounted hydraulic cylinder with plunger therein for propelling the ram 55 which produces the bore, substantially as and for the purpose described.

3. An earth boring machine, comprising tubular members with screwed extensions for clamping the same in the pit adjacent the mouth of the bore to be produced, a 60 frame carried by said members and abutting against the wall of the pit opposite the bore, slots in said frame, a hydraulic cylinder having trunnions thereon which enter the said slots, the cylinder abutting against the 65 said frame at its rear end and the abutting faces being curved so as to permit of the rotation of the cylinder about the axis of its trunnions, and a clamp on the frame for the front end of the cylinder, substantially 70 as described.

4. In an earth boring machine as defined by claim 1, the provision of pivotal catch pieces upon the hydraulic plunger designed to detachably secure a pipe to said plunger. 75

5. In an earth boring machine of the kind defined by claim 2, pivotal catch pieces provided upon the end of the plunger designed to detachably secure the end of a pipe to 80 said plunger.

6. In an earth boring machine of the kind defined by claim 1, the arrangement whereby the frame, cylinder, and its plunger can be utilized for withdrawing pipes from a bore or for drawing pipes, cables or the 85 like through the latter.

7. In an earth boring machine as defined by claim 2, means combined with said frame, cylinder and its plunger for withdrawing pipes from a bore or for drawing pipes, cables or the like through the latter. 90

8. In an earth boring machine, the combination with a portable frame having means for clamping its ends between opposite walls of a pit, a second frame coöperating with the first frame and movable into positions substantially parallel to and at substantially right angles to the first frame, a hydraulic cylinder pivotally mounted in the second frame, and a plunger mounted in 100 said cylinder. 95

9. A combination as defined in claim 8 in which the cylinder and the plunger are arranged at substantially right angles to the first frame, a pulley carried by the first 105 frame, a pulley carried by the plunger, and a rope passing over the pulleys and having one of its ends fixed to one of the frames.

In testimony whereof we have signed our names to this specification.

ARTHUR RIVINGTON MANGNALL.
ROY FORBES IRVING.
